UNITED STATES PATENT OFFICE

2,436,353

ADJUSTABLE LUG STRAP

W. Irving Bullard, Charlotte, N. C., assignor to
 E. H. Jacobs Mfg. Co. Inc., Danielson, Conn.,
 a corporation of Connecticut

Application November 7, 1946, Serial No. 708,283

1 Claim. (Cl. 139—153)

1

My present invention is a novel and improved lug strap particularly employing a plug adjustably secured to the side arms or frame portion of a lug strap and, furthermore, providing a novel arrangement for adjustment for length of the entire lug strap at the plug or heel end.

Heretofore, in the use of lug straps for transmitting power to a picker stick in standard types of looms, it has been customary to form the lug strap construction of generally U-shaped contour and, preferably, with a plug or block permanently fitted at the heel or bottom of the U formation, the extending arms being provided near their open ends with slots to allow for adjustment of length desired when attaching the lug strap onto the actuating link or operative part of the loom which gave the lug strap its impetus to throw the picker stick across the loom during the weaving operation.

Such prior constructions were objectionable in various features. The provision of the slots for adjustment of length at the open end of the arms caused considerable difficulty in effecting the adjustments as desired from time to time, as these slots were within the area of the loom and, consequently, access thereto was difficult. Also, such prior adjusting capacity resulted in considerable guesswork to determine the proper distance between the power link operating the lug strap and the face of the plug or block against which the picker stick would strike.

A further prior difficulty was that occasioned by the customary riveting of the plug at the heel of the U-shaped arms, the plug of such prior constructions being rigidly attached, and, when worn down to the first rivet rendered the entire lug strap useless.

In my present improved and adjustable lug strap I provide a more convenient and quickly accessible construction for the lengthwise adjustment, said adjustment means being at the plug end or heel of the lug strap which ordinarily extends free of the rest of the machine and out into the passageway or alley where a bank of looms are installed. Furthermore, my present invention provides quickly adjustable means to compensate for wear on the face of the plug as well as stretch or wear on the extending arms where the bolt is attached to the power link.

A still further feature and advantage of the present construction consists in a longer and larger mass of the plug material allowing for wear of the striking face of the plug on the lug strap.

By my present construction I utilize a single

2

square or hexagonal bolt extending thru a lug strap to hold the same rigid and in proper relation to the side arms interlocking the plug and side arms into firm position at any lengthwise adjusted position of the plug and arms.

A further novel feature of my present adjustable lug strap is that I may streamline, taper, or otherwise form the side arms so as to impart a predetermined "whip," spring, and drive to the lug strap and, hence, through the picker stick to the shuttle.

Heretofore it has been considered essential to rely on the resilience or elasticity of the picker stick to predetermine "whip" and spring in its operation on the shuttle of a loom, but by my present invention I may utilize the arms of the lug strap itself either alone or in cooperation with the form, structure, and resiliency of the picker stick to effectively provide and, preferably, predetermine the desired whip, spring, and resiliency of the shuttle-throwing operation.

I may form my lug strap arms and plug of any suitable material. Thus the arms may be of wood, synthetic plastic, canvas, leather, rubber, metal, or a combination of the same, and such material may be formed either as a substantial solid mass, or laminated where wood is employed, or inter-rolled where canvas is used. The plug may be also of any suitable material as a block of wood, leather, rubber, plastic which may be enclosed in rubber or canvas if desired, or may be of laminated layers of wood, leather, rubber, or synthetic plastic material.

Referring to the drawings:

Fig. 1 is a plan view partly in cross-section illustrating my novel and improved adjustable plug lug strap;

Fig. 2 is a side view;

Fig. 3 is a side view partly in cross-section illustrating streamlined and tapered arms of inter-rolled canvas;

Fig. 4 is a cross-sectional view on the line 4—4 of Fig. 1, and

Fig. 5 is a view on the line 5—5 of Fig. 1 with the adjacent arm removed.

Fig. 6 is a perspective view of a modified form of washer.

Referring to the drawings, a pair of side arms 1 and 2, herein shown of wood or synthetic plastic material, are provided with an intermediate plug 3 formed of laminated wear-resisting material, preferably wooden layers impregnated with synthetic plastic to strengthen, preserve, and unite the same as well as giving them a wear-resisting surface particularly on the inner edge 5 of the

plug, which is herein illustrated as slightly convex, as is usual. The arms 1 and 2 are provided with bolt-receiving holes 6 and 7 at the open ends of the arms; and at the opposite ends lengthwise slots 8 and 9 are formed centrally in the arms 1 and 2, respectively, to allow for lengthwise adjustment of the plug 3. The plug 3 is fitted with a square, hexagonal, or oval bolt 10 thru a correspondingly formed bolt sidewise of the plug 3 and it is thus adapted to hold the plug 3 firmly and rigidly in position when the ends of the bolt 10, which are rounded and threaded for the purpose as indicated at 11, are each fitted with nuts 12 bearing against a washer 14 which spans the openings 8 and 9, and thus constitute means to interlock the plug 3 and arms 1 and 2 when the nuts 12-12 are tightened. To effect lengthwise adjustment relatively between the plug 3 and arms 1 and 2, the nuts 12-12 are loosened and the plug shifted, the shank of each end of the bolt 10 traversing the slots 8 and 9 respectively.

In order to more fully interlock the plug 3 and arms 1 and 2, I provide a pronged washer 15 having a square opening in the center, as best shown at 16, Fig. 5, so that the same is rigid on the bolt 10 and, hence, firmly fixed on the plug 5, this washer having a plurality of prongs 20 extending therefrom and adapted to impinge into or to be buried slightly in the adjacent side face of the arm 1 or 2, respectively, as shown. This construction adds further to maintain the plug and arms in proper position in addition to the squared shank of the bolt 10, as will be readily appreciated.

In Fig. 3, I have illustrated a tapered and streamlined form of arms 21 and 22 formed of interrolled canvas with the single slots 23 and 24 at one end to receive a bolt which acts as a pivot between the lug and power link connecting the same and with lengthwise adjusting slots 25 and 26, respectively, at the opposite end to receive the squared or non-rotating bolt 10 with its fastening means.

In this form I have also illustrated a tapered and streamlined form which may be effective to predetermine the whip and spring in the lug strap itself, although the material of the lug strap, being properly and scientifically constructed to provide whip and spring in the action of the lug strap on the picker stick, can be secured in any desired way by the strength and resiliency of the material employed.

As shown in Fig. 6, I have illustrated a modi-

fied form of locking and pronged washer 30 to aid in interlocking the plug 5 to the arms 1 and 2 or 21 and 22. For this purpose, the washer 30 has a squared opening in the center 31, a plurality of prongs 32 similar to the construction of the washer 15 already described but with the body or plate portion of the washer 30 extended sufficiently to have edge flanges 33 turned up therefrom in position to fit over and engage the outside edges of the arms at each side. Thus, these flanges 33 still further aid in holding the arms and plug rigidly in alignment in addition to the squared bolt 10 and lock nuts 12.

I claim:

15 A lug strap of the kind described, having a pair of longitudinally extending arms of canvas, wood, plastic, or the like non-metallic material, and a plug formed of a plurality of layers of yieldable material with centrally arranged recesses thru each layer in alignment and non-circular in cross-section, both said arms and plug being separable from each other, means to assemble said arms and plug in operative position to constitute a lug strap in a loom, in combination with fastening means to hold said plug and non-metallic arms in alignment when assembled as a lug strap, said fastening means comprising a non-rotatable bolt registering with the non-rotatable openings thru said plug layers, and a pair of washers fitted to the bolt in non-rotatable engagement therewith between the sides of the plug and the arms, said washers having upstanding flanges to engage the opposite edges of adjacent arms and a plurality of upstanding points to penetrate said arms.

W. IRVING BULLARD.
